EDUCATIONAL POP-UP TOY

Reuben B. Klamer, Pacific Palisades, and Donald W. Herrick, Lawndale, Calif., assignors to Link Research Corporation, Beverly Hills, Calif., a corporation of California

Filed Mar. 1, 1960, Ser. No. 12,074

2 Claims. (Cl. 35—22)

This invention relates to a pop-up toy and more particularly to a toy simulating a typewriter and having a plurality of simulated type keys positionable on the toy and ejectable from the toy in pop-up fashion.

This invention provides a toy designed more particularly for children at the age level at which they begin to discern and match configurations of objects relative to sockets therefore, i.e., a "square block in a square hole" stage, which is also the age level at which children delight in knocking down or knocking apart structures which they have stacked or constructed. It is an age level at which it has been found that a child enjoys particularly to see objects flying upwardly into the air in reaction to his effort. Since this age level also includes the beginning of the ability to discern configurations of objects, the invention further provides an educational value by requiring such distinction by the child in order to assemble the toy before it can be knocked apart or popped up.

Therefore, it is an object of this invention to provide a new and improved pop-up toy which provides improved educational value while providing amusement for children at the above mentioned age level.

Another object of this invention is to provide improved manually operable means for ejecting objects, in the form of simulated type keys, from a top, simulating a typewriter, in pop-up fashion which is easily and readily operable.

It is a further object of this invention to provide objects ejectable by the manually operated means and openings therefor, in which the objects are insertable for engagement by an ejector means, whereby recognition of the configuration of the object relative to a complementary opening is required by the child in order to assemble the toy before it can be actuated to pop up.

A further object of this invention is to provide a new and improved pop-up toy, of the character described, which is economical to manufacture and capable of mass production.

A still further object of this invention is to provide means on the objects themselves causing the objects to fly in a pre-determined direction upon actuation of the ejection means.

These and other objects of this invention will be more apparent from the following detailed description, drawings and appended claims.

In the drawings:

FIG. 1 is a perspective view, in elevation, of a pop-up toy designed and constructed in accordance with this invention with an element thereof illustrated in exploded position for greater clarity.

FIG. 2 is a vertical, cross-sectional view, as taken substantially along the line 2—2 of FIG. 1;

FIG. 3 is a fragmentary bottom view of the toy of FIG. 1;

FIG. 4 is an enlarged, fragmentary, vertical cross-sectional view taken substantially along the line 4—4 of FIG. 3;

FIG. 5 is an enlarged, fragmentary, vertical cross-sectional view, taken substantially along the line 5—5 of FIG. 3;

FIG. 6 is an enlarged, fragmentary, vertical cross-

2

sectional view taken substantially along the line of 6—6 of FIG. 2;

FIG. 7 is a vertical cross-sectional view, similar to the left portion of FIG. 2, showing portions thereof in a changed position; and

FIG. 8 is an enlarged perspective view, in elevation, showing an element of the invention in greater detail.

Referring in detail to the drawings, there is shown, by way of illustration, but not of limitation, a pop-up

10 toy, generally designated by the numeral 10 and designed and constructed in accordance with this invention. The toy 10 comprises a hollow housing 11 having an outer appearance generally simulating an actual typewriter and including a top wall 12, side walls 13, a front wall 14 and an open bottom 16, the open bottom 16 being closed at the bottom by a removable, or optionally permanently secured, bottom wall 17. The housing 11 is preferably molded, die cast, or otherwise formed of an easily formable material, such as plastics or the like, and preferably of a high impact plastics material which is capable of rough usage normally associated with children at the age level for which the toy is intended.

One of the features of this invention is the provision of educational means requiring distinction by the user of 25 various forms and configurations to place objects in a position for ejection from the housing.

For this purpose, a plurality of openings 17 are formed in the top wall 12, each opening 17 having a different configuration, the configurations illustrated herein closely 30 resembling letters of the alphabet. For convenience, inasmuch as the top wall 12 is sloped downwardly to simulate a typewriter, a plurality of bosses 18 extend substantially vertically, through which the openings extend as best seen in FIGURES 1, 2 and 7.

35 A plurality of plugs 19, simulating type keys, are provided for insertion into the openings 17, each plug 19 having a configuration complementary to the configuration of one of the openings 17. Each plug 19 includes a hollow body of a high impact material, such as plastics, 40 or the like, which includes a depending boss 21 having an outer geometrical configuration complementary to and detachably fitting one of the openings 17, such as the plug 19 having a configuration of the letter D matching the opening 17 likewise having a configuration complementary thereto in the form of a letter D as it appears when cut out of the top surface 22 of its boss 18. To prevent the plug 19 from falling through the opening 17 into the interior housing 11, a flange 23 is provided on an intermediate portion of the plug 19 and appreciably 45 larger than the opening 17. A plurality of lugs are provided on the side of the flange 23 to keep the flange 23 spaced above the top surface 22 whereby the plug 19 is more easily dislodged from its opening 17. An upwardly 50 extending boss 26, having a configuration matching that 55 of the lower portion 21 is provided above the flange 23 whereby the plug 19 may be identified by the configuration of the upper boss 26 to aid in matching one plug to its respective opening 17.

As best seen in FIGS. 7 and 8, each plug 19 is preferably cast or otherwise formed in hollow form with an open bottom 27 and a web 28 integrally or otherwise secured and extending intermediately across the opening 27, each web 28 having cam surfaces 29 for a purpose which will be hereinafter described.

60 In this manner, the toy 10 provides educational means for aiding in the development of the mind of the user by the requirement of distinguishing between the configurations of plugs for insertion thereof into matching openings 17. The bosses 26 above the flanges 23 are 65 preferably appreciably shorter than the depending bosses 21 whereby further discrimination is required in that the plug will either not match its respective opening

if an attempt is made to insert the plug in an upside down condition, e.g., the letters B, C, and Z, or, in other forms, e.g., the letters A, D, W, X and Y, which can be ostensibly inserted in an upside down position, can not be ejected from the opening due to the length of the bosses 26 and the limited action of the ejection means, as will be more apparent from the following description.

After the various plugs or keys 19 have been properly inserted, means are provided whereby the child may eject the plugs or cause them to pop-up upwardly from their openings 17 as a source of amusement. For this purpose an ejector means 31 is pivotally mounted within the housing 11 and actuatable by a manually operable actuator means 32 extending outwardly of the housing which, upon actuation, causes the plugs 19 to be ejected or popped up outwardly of their respective openings 17, and away from the housing 11.

The ejector means 31 includes a frame 33 pivotally mounted in the housing 11 for arcuate movement towards and away from the top wall 12. The frame 33 includes a transverse member 34 having a plurality, four in number herein illustrated, of spaced rearwardly-extending arms 36, each arm having a pair of spaced, upwardly-extending posts 37 secured thereto or integral therewith. Each post 37 is aligned with one of the openings 17. The frame 33 further includes a plurality of forwardly-extending arms 38, selective arms 38 being connected by shafts 39 which are rotatably supported in depending lugs 41 integral with or secured to the underside of the top wall 12 of the housing. To facilitate assembly, the lugs 41 are preferably provided with open-ended slots 40 adapted to receive the shafts 39 through a constricted opening whereby the shafts 39 are snapped into place to pivotally mount the frame 33. The frame 33 further includes a forwardly-extending lug or arm 42 engageable with the underside of the actuator means 32 for translating downward pivotal movement of the actuator means 32 to an upward movement of the ejector means 31.

The ejector means 31, when pivoted upwardly, bring the posts 37 into contact with the cam surfaces 29 of their respective plugs 19 to impart an impact to the plugs and eject them outwardly of their respective openings 17 and away from the housing 11. The cam surfaces 29 of the plugs 19 are angularly disposed so as to cause the parts 19 to be projected forwardly as well as upwardly and towards the front of the housing. It is to be understood that the cams 29 may be optionally varied so as to project the plugs 19 in any desired direction, such as rearwardly or sidewardly, or combinations thereof, if desired.

The actuator means 32 includes a manually operable transverse bar 43 extending outwardly of the housing for manual manipulation thereof. The actuating means 32 includes a pair of arms 44 extending rearwardly through a slot 46 of the front wall 13 of the housing for pivotal securing to the housing by means of pins 47 snapped into open-ended, restricted slots 48 of a pair of depending lugs 49 of the housing 11, as best seen in FIG. 5.

The forwardly-extending arm 42 of the frame 33 extends beneath the bar 43, as best seen in FIG. 4, for engagement therewith, whereby downward pivotal movement of the arm 43, as caused by the sharp striking thereof by a child, causes the arm 42 to be pivoted downwardly around the axes of the shafts 39 and thereby the inner portion of the frame 33, having the transverse member 34 and arms 36, to swing upwardly to cause the posts 37 to come into contact with the plugs 19 inserted into the openings 17. Release of the bar 43 causes the inner portion of the frame 33 to drop downwardly, by the force of gravity, to the normal position shown in FIG. 2 and as determined by abutment of the arm 42 with the bar 43 which is limited by the upper portion of the slot 46 engaging the arm 44 as at 51 to stop the pivotal movement of the frame in its downward direction and the arm 42 in its upward

75 pivotal movement. The downward pivotal movement of the bar 43 is limited by engagement of the lower portion of the arm 44 with the lower end of the slot 46.

To further add to the enjoyment and amusement of the user, a sound-producing means 52 is provided and responsive to pivotal movement of the frame 33 to produce a sound when the ejector means 31 is actuated to eject the plugs 19. The sound-producing means 52 includes a resonator 53 secured to the housing as at 54 and engageable by a hammer 56 resiliently secured to the ejector means 31 for striking the resonator. The hammer 56 is resiliently mounted by a coil spring 57 having a friction engagement at one end with a pin 58 on the hammer 56 and a similar fit at its other end with a pin 59 extending rearwardly from the ejector means frame 33.

To add further realism to the appearance of the toy 10, for simulating a typewriter, and to thereby provide further amusement to the user, a simulated cylindrical platen 60 is rotatably secured by stub shafts extending outwardly of its ends and into restricted slots 61 of the housing 11. The platen 60 includes a knob 62 secured to the outer end of each shaft 63 for manually-imparted rotation thereof. A serrated or toothed disc 64 is integrally formed with the platen 60, or is optionally secured thereto, for rotation therewith, the disc 64 being in engagement with an end of a clicker member 66 secured within the housing 67 and having the end 68 extending outwardly of the housing for engagement with the wheel 64. As the platen 60 is rotated, the wheel causes the clicker member 66 to produce a clicking sound. Additionally, if desired, indicia, as indicated at 69, may be provided on the platen 60 to aid in the education of the user.

While we have herein shown and described our invention in what we have conceived to be the most practical and preferred embodiments, it is recognized that departures may be made therefrom within the scope of our invention, which is not to be limited to the details disclosed herein but is to be accorded the full scope of the claims so as to embrace any and all equivalent devices and methods.

What we claim as new and desire to secure by Letters Patent is:

1. A pop-up toy comprising: a housing having an outer configuration resembling a typewriter and having a top wall and side walls, said top wall having a plurality of openings extending therethrough; a plurality of plugs detachably fitting said openings; an ejector means pivotally secured in said housing and having a plurality of upstanding posts, each aligned with one of said openings; manually operable actuator means pivotally mounted in said housing and having a handle portion extending outwardly of said housing for manipulation thereof, said ejector means being engageable by said actuator means and responsive to pivotal movement of said actuator means in one direction, so as to pivot upwardly and adjacent said top wall, and engage each of said posts with its respective plug so as to eject said plugs outwardly from said openings, each of said plugs being hollow and including a transverse web having a cam surface and said posts being so aligned as to engage said cam surface of said webs during upward pivotal movement of said ejector means and said cam surface being angular so as to direct said plugs outwardly of their respective openings in predetermined direction.

2. A pop-up toy comprising: a housing having an outer configuration resembling a typewriter and having a top wall and side walls, said top wall having a plurality of openings extending therethrough; a plurality of plugs detachably fitting said openings; an ejector means pivotally secured in said housing and having a plurality of upstanding posts, each aligned with one of said openings; manually operable actuator means pivotally mounted in said housing and having a handle portion extend-

ing outwardly of said housing for manipulation thereof, said ejector means being engageable by said actuator means and responsive to pivotal movement of said actuator means in one direction, so as to pivot upwardly and adjacent said top wall, and engage each of said posts with its respective plug so as to eject said plugs outwardly from said openings, each of said plugs being hollow and including a transverse web having a cam surface and said posts being so aligned as to engage said cam surface of said webs during upward pivotal movement of said ejector means; said cam surface being angular so as to direct said plugs outwardly of their respective openings in predetermined direction, and flange means on said plugs, said flange means being appreciably

larger than said openings so as to limit insertion of said plugs in said openings, whereby a lower portion of each plug extends into said housing and is engageable by said posts.
